Primary Examiner — T. Chase Nelson(74) *Attorney, Agent, or Firm* — Squire Patton Boggs (US) LLP(57) **CLAIM**

The ornamental design for a shoe sole, as shown and described.

DESCRIPTION

FIG. 1 is a bottom plan view of a shoe sole in accordance with the new design;

FIG. 2 is a bottom, rear, and left side perspective view of the detail area "2" of FIG. 1 thereof; and,

FIG. 3 is a rear cross-sectional elevation view of the line 3-3 of FIG. 1 thereof.

The broken lines of FIGS. 1 and 3 illustrate the bounds of the claimed design. Both the broken line boundary and the area outside the broken line boundary form no part of the claimed design.
